US00D710048S

(12) **United States Design Patent**
Randolph et al.

(10) **Patent No.:** **US D710,048 S**
(45) **Date of Patent:** **** Jul. 29, 2014**

(54) **LIGHTING FIXTURE LENS**

(75) Inventors: **David N. Randolph**, Rougemont, NC (US); **John R. Rowlette, Jr.**, Raleigh, NC (US)

(73) Assignee: **Cree, Inc.**, Durham, NC (US)

(**) Term: **14 Years**

(21) Appl. No.: **29/408,234**

(22) Filed: **Dec. 8, 2011**

(51) LOC (10) Cl. **26-99**

(52) U.S. Cl.

USPC **D26/120**

(58) **Field of Classification Search**

(57) **CLAIM**

The ornamental design for a lighting fixture lens, as shown and described.

DESCRIPTION

FIG. 1 is a first isometric view of a lighting fixture lens.

FIG. 2 is a second isometric view of the lighting fixture lens of FIG. 1.

FIG. 3 is a plan view of a first side of the lighting fixture lens of FIG. 1.

FIG. 4 is a plan view of a second side of the lighting fixture lens of FIG. 1.

FIG. 5 is a plan view of a third side of the lighting fixture lens of FIG. 1.

FIG. 6 is a plan view of a fourth side of the lighting fixture lens of FIG. 1.

FIG. 7 is a plan view of a top of the lighting fixture lens of FIG. 1; and,

FIG. 8 is a plan view of a bottom of the lighting fixture lens of FIG. 1.

The broken lines shown in the drawings depict portions of the lighting fixture lens that form no part of the claimed design.

1 Claim, 2 Drawing Sheets
